(57) **CLAIM**

The ornamental design for an animal crate bumper, as shown and described.

DESCRIPTION

FIG. 1 is a perspective view of an animal crate bumper, showing my new design within an environmental structure, namely, an animal crate having a different configuration than the animal crate bumper, wherein the animal crate bumper has been configured in a first position to fit the environmental structure;

FIG. 2 is a perspective view showing the animal crate bumper of FIG. 1 without the animal crate;

FIG. 3 is a top plan view thereof;

FIG. 4 is a right side view thereof;

FIG. 5 is a rear elevational view thereof;

FIG. 6 is a front elevational view thereof;

FIG. 7 shows an alternate position of the animal crate bumper shown within the environmental structure, where the animal crate bumper has been configured in a second position to fit the environmental structure;

FIG. 8 is a perspective view on the animal crate bumper of FIG. 7, shown without the animal crate;

FIG. 9 is a top plan view thereof;

FIG. 10 is a right side view thereof;

FIG. 11 is a rear elevational view thereof; and,

FIG. 12 is a front elevational view thereof.

The alternating long and short dashed broken lines shown in FIG. 1 and FIG. 7 represent environmental structure, namely, an animal crate within which the animal crate bumper is placed and form no part of the claimed design.

(Continued)

The short dotted lines seen on the surfaces of the animal crate bumper represent stitching that forms part of the claimed design.
